CLAIM

The ornamental design for a bottle infusing tool, as shown and described.

DESCRIPTION

FIG. 1 is a front elevation view of a bottle infusing tool showing our new design, a rear elevation being a mirror image thereof;

FIG. 2 is a left side elevation view, a right side elevation view being a mirror image thereof;

FIG. 3 is a top view of the bottle infusing tool of FIG. 1; FIG. 4 is a bottom view of the bottle infusing tool of FIG. 1;

FIG. 5 is a sectional view of the bottle infusing tool of FIG. 1; taken in the direction of line 5-5 on FIG. 3; and, FIG. 6 is a top perspective view of the bottle infusing tool of FIG. 1.
